E. G. LABARRE

DISPLAY RACK

Filed June 9, 1924

Inventor
Eugene G. Labarre

33, Whittmore Hulbert Whittmore
Belknap Attorney

UNITED STATES PATENT OFFICE.

EUGENE G. LA BARRE, OF DETROIT, MICHIGAN.

DISPLAY RACK.

Application filed June 9, 1924. Serial No. 718,912.

This invention relates generally to display racks and refers more particularly to those of the adjustable type.

One of the essential objects of the invention is to provide a display rack of this type that is preferably formed of a plurality of separate arms which may be readily attached to a suitable support and which may be easily and quickly adjusted when attached to 10 accommodate articles of different sizes and thicknesses.

Another object is to provide a display rack having arms that are preferably formed of telescoping sections which may be readily collapsed when not in use or for shipment.

A further object is to provide a strong and durable display rack that is simple in construction and that can be manufactured at a comparatively low cost.

With the above and other objects in view the invention consists in certain novel features of construction, combinations and arrangements of parts as will be more fully described and particularly pointed out in 25 the appended claims.

In the accompanying drawing:

Figure 1 is an elevation of a display rack embodying my invention secured to a wall;

Figure 2 is a perspective view of one of 30 the arms of the display rack.

Figure 3 is a section on the line 3—3, Figure 2.

Figure 4 is a section on the line 4—4, Figure 2.

Referring now to the drawing in which like characters of reference designate corresponding parts throughout the several views, the numeral 1 designates a display rack embodying my invention for holding 40 post cards, music, books, periodicals and other articles upon a suitable support such as a wall 2.

The rack may be formed of any suitable material and is preferably formed of three 45 arms 3 which are preferably arranged at right angles to each other upon the wall as shown in Figure 1 of the drawing.

Each arm 3 preferably comprises a series of sections 4, 5, 6 and 7 respectively 50 having telescopically engaging open return-bent flanges 8 at the top and bottom edges thereof providing for variation of the combined length of the sections. In order that each arm 3 may be readily attached to the 55 wall 2, the top and bottom flanges 8 of the

section 4 preferably project beyond one end of the said section and are provided with suitable openings 9 for receiving the headed securing elements 10 which are driven into the wall 2.

In order that the sections of each arm 3 may be easily and quickly assembled so that they cannot be pulled apart while being extended, I preferably provide a series of 60 spring tongues 10, 11, and 12 respectively 65 that are preferably struck out from the sections 4, 5 and 6 respectively. To give stability to these sections when extended the tongues are preferably spaced about one-quarter of an inch from the outer end of 70 each section. As shown, the tongue 10' preferably engages a longitudinally extending slot 13 in the section 5; the tongue 11 is offset with respect to the tongue 10' and engages a longitudinally extending slot 14 in 75 the section 6, while the tongue 12 is offset with respect to the tongues 10' and 11 and engages a longitudinally extending slot 15 in the section 7.

In order that articles of various thicknesses may be held by the arms 3 of the rack, I preferably provide each arm with an elbow 16 that preferably extends at right angles thereto. As shown, each elbow 80 preferably comprises the sections 17 and 18 respectively. The sections 18 are preferably provided at their outer ends with transversely extending flanges 19 for holding the articles to be carried by the rack, while the sections 17 are provided with open return-bent flanges 20 at the top and bottom edges 90 thereof telescopically engaging the upper and lower edges of the sections 18. For limiting the sliding movement of the sections 18, I preferably provide suitable spring 95 tongues 21 that are struck out from the sections 17 and engage longitudinally extending slots 22 in the sections 18.

For securing the elbows 16 to the arms 3, I preferably provide short spring tongues 23 100 that are preferably struck out from the sections 7 and engage suitable openings 25 in transversely extending flanges 24 at the inner ends of the sections 17. The elbows are preferably packed and shipped separately 105 from the arms 3 and are subsequently assembled when it is desired to set up the rack by merely inserting the flanges 24 of the sections 17 between the upper and lower flanges 8 of the end section 7 whereupon the 110

tongues 23 will spring into the opening 25 in the sections 7 to securely hold the elbows to the arms.

In use, the sections 4 of the assembled arms 3 may be secured to the wall in whatever position desired, whereupon the movable sections of the arms may be adjusted inwardly and outwardly to accommodate articles of different length and width and the sections 18 of the elbows may be adjusted to accommodate articles of different thicknesses.

While it is believed that from the foregoing description, the nature and advantages of the invention will be readily apparent, I desire to have it understood that I do not limit myself to what is herein shown and described and that such changes may be resorted to when desired as fall within the scope of what is claimed.

What I claim as my invention is:

1. A display rack comprising a plurality of supporting arms, each arm having sections provided with telescopically engaged open return-bent flanges at the top and bottom edges thereof providing for variation of the combined lengths of the sections, and a laterally extending sectional elbow connected to each arm having a flange substantially parallel to said arms for holding the articles carried by said arms.

2. A display rack comprising a plurality of supporting arms, each arm having an adjustable section, flanges projecting from one section of each arm, the other sections of each arm having longitudinally extending slots, tongues struck out from certain of the sections of said arm engaging said slots, an elbow connected to one section of each arm for supporting articles upon said arms, and means carried by said elbows for holding the articles carried thereby.

3. A display rack comprising a plurality

of separate supporting arms, each arm having a plurality of adjustable sections, certain sections of each arm having longitudinally extending slots arranged in staggered relation, and spring tongues struck out from other sections of said arm engaging said slots for retaining the sections in engagement while being expanded.

4. A display rack comprising a plurality of independently mounted collapsible supporting arms, each arm consisting of a plurality of sections adapted to telescopically engage each other for longitudinal adjustment, each of said arms having a detachable elbow extending at right angles thereto, means for detachably securing the elbow to said arms including spring tongues struck out from one of said sections and adapted to engage said elbow, said elbow consisting of a plurality of adjustable sections adapted to telescopically engage each other for adjustment laterally, and an article holding means carried by one of said last mentioned sections of said elbow.

5. In a display rack, the combination of a base, a plurality of separated supporting arms mounted on said base in angular relation to each other, each of said arms comprising a plurality of telescoping sections, the end of the outermost section of each of said arms being bent outwardly and backwardly to form an article holding means.

6. In a display rack, the combination of a base, a plurality of separated supporting arms mounted on said base in angular relation to each other, each of said arms comprising a plurality of telescoping sections, and a telescoping return bent elbow on each end section constituting article holding means.

In testimony whereof I affix my signature.

EUGENE G. LA BARRE
